No. 611,281.

Patented Sept. 27, 1898.

O. ROSE.

SHIPPING CRATE.

(Application filed Oct. 25, 1897.)

(No Model.)

UNITED STATES PATENT OFFICE.

OREN ROSE, OF GIBSON, NEW YORK.

SHIPPING-CRATE.

SPECIFICATION forming part of Letters Patent No. 611,281, dated September 27, 1898.

Application filed October 25, 1897. Serial No. 656,308. (No model.)

To all whom it may concern:

Be it known that I, OREN ROSE, a citizen of the United States, residing at Gibson, in the county of Steuben and State of New York, 5 have invented a new and useful Shipping-Crate, of which the following is a specification.

My invention relates to shipping-crates of the folding or knockdown type, and the object in view is to provide a crate having no 10 detachable parts and which may be folded into compact form for return shipment.

Furthermore, my invention is particularly applicable to that class of crates wherein no 15 lids or covers are employed to provide for filling the crates above the level or "struck" measure, the object in view being to provide such a construction of folding-crate bottom that when crates embodying my invention are 20 tiered the upper crates will not injure the contents of the lower or supporting crates.

Further objects and advantages of this invention will appear in the following description, and the novel features thereof will be 25 particularly pointed out in the appended claims.

In the drawings, Figure 1 is an end perspective view, partly in section, of a crate constructed in accordance with my invention, the folded positions of the side walls being 30 indicated in dotted lines. Fig. 2 is a longitudinal section of the same, showing in dotted lines the folded positions of the end walls. Fig. 3 is a detail horizontal section of the 35 joint between contiguous side walls. Fig. 4 is a detail vertical section of a portion of one end of the crate, showing the contiguous end wall in its folded position.

Similar numerals of reference indicate corresponding parts in all the figures of the drawings.

The bottom wall 1 of the crate embodying my invention is provided with longitudinal side bars or cleats 2, forming hinge-bars, upon which are mounted the movable or folding 45 sections 3 of the side walls, the latter being provided with inner guide-cleats 4, pivotally mounted at their lower extremities upon the ends of said hinge-bars, and with outer guide-cleats 5, which are respectively parallel with 50 the inner guide-cleats and are spaced therefrom to form intermediate guideways, in which are mounted to slide the contiguous edges of

the end walls 6. The side bars or cleats 7 of said end walls project at their outer edges beyond the contiguous extremities of the slats 55 of said walls to fit in the guideways, and stops 8 are arranged at the upper ends of the guideways to limit the upward movement of the end walls, said stops in the construction illustrated consisting of transverse pins. 60

As above indicated, the side walls are of sectional construction, with the folding sections 3 pivotally mounted to fold inwardly to occupy a position parallel with the bottom wall, as indicated in dotted lines in Fig. 1; 65 but in order to prevent outward folding of these movable side-wall sections I provide the end walls with T-head guides 9, fitting in registering guide-grooves 10 in opposite walls of the guideways. In the construction illustrated these T-head guides consist of anti-friction roller-disks mounted upon spindles 11, arranged parallel with the planes, respectively, of the end walls, whereby the disks are arranged in planes parallel with the 70 normal positions of the side walls. 75

The fixed or permanent sections 3^a of the side walls depend below the plane of the bottom wall, and the guideways, which are formed on the extremities of the movable side-wall sections, are extended upon said fixed or permanent sections to allow the T-head guides, which are arranged contiguous to the upper edges of the end walls, to pass downward to a point below the plane of the bottom wall, 80 and thus wholly release the movable side-wall sections. Inasmuch as the interposition of the end walls between the planes of the side walls serves normally to hold the side walls in their upright or operative positions, it will 85 be understood that the disengagement of the end walls by the downward-sliding movement thereof to a point below the plane of the bottom wall will allow the inward folding of the side walls to the position indicated in dotted 90 lines in Fig. 1. 95

The inner walls of the guideways on the side walls, said inner walls being formed by the inner guide-strips 4, are omitted below the plane of the bottom wall, whereby when the end walls reach the depressed position above described they are free to fold inwardly or toward each other between the depending portions 3^a of the side walls upon the axes 100

- formed by the disks 8, thus adapting the end walls to fold into planes parallel with the bottom wall and between the planes of the side walls, where they are protected and are compactly arranged for return shipment. In order to facilitate the engagement of the T-head guides with the guideways, I cut away portions of the inner surfaces of the fixed sections 3^a of the side walls to form recesses 12; but engagement or disengagement of the said guide-disks with the guideways can be accomplished only when the end wall which is to be inserted or removed is twisted out of its normal position to depress the guide-disk at one of its edges to a point below the plane of the other. When in their normal positions, the end walls are arranged with their lower edges flush with the corresponding edges of the side walls to prevent accidental depression thereof and also to form a continuous bearing for the several walls of the crate, whereby when the crates are tiered the bottom of an upper crate does not bear upon the contents of the subjacent crate.
- 25 It will be seen that the bottom of the crate embodying my invention is upset from the plane of the lower edges of the side and end walls to form a cavity adapted to receive a portion of the contents of a subjacent crate 30 when the latter is filled to a point above the plane of the upper edges of its walls.

Various changes in the form, proportion, and the minor details of construction may be resorted to without departing from the spirit 35 or sacrificing any of the advantages of this invention.

Having described my invention, what I claim is—

1. A crate having a bottom wall, side walls 40 mounted upon the bottom wall to fold inwardly and provided with terminal transversely-aligned guideways, and end walls fitted to slide at their edges in said guideways on the side walls, and adapted to be downwardly 45 withdrawn therefrom to fold in planes parallel with the bottom wall, substantially as specified.

2. A crate having a bottom wall, inwardly-folding side walls provided with transversely-aligned guideways, end walls fitted at their side edges to slide in said guideways, and adapted, when withdrawn downwardly, to fold parallel with the plane of the bottom wall, and means for limiting the upward-sliding 55 movement of the end walls, substantially as specified.

3. A crate having a bottom, side walls mounted upon the bottom to fold inwardly, and provided with terminal transversely-aligned guideways, guideway extensions arranged below the plane of the bottom wall, end walls fitted to slide at their side edges in

said guideways, and means carried by the end walls for pivotally supporting the same in said extensions of the guideways, substantially as specified. 65

4. A crate having a bottom wall, inwardly-folding side walls provided with terminal transversely-aligned guideways, end walls fitted to slide at their side edges in said guideways, and a T-head guide swiveled upon the end walls at each edge, to fit in aligned grooves in the side walls of said guideways to prevent outward deflection of the side walls, substantially as specified. 70

5. A crate having a bottom wall, sectional side walls comprising inwardly-folding pivotal sections mounted upon the bottom wall, and fixed sections depending below the plane of the bottom wall, said pivotal sections being 80 provided with terminal transversely-aligned guideways, end walls fitted at their side edges to slide in said guideways, and end-wall-pivoting devices carried by said end walls near their upper edges and adapted, when the side 85 edges of the end walls are disengaged from the guideways of said pivotal sections, to pivotally support the end walls for upward folding parallel with the plane of the bottom wall, substantially as specified. 90

6. A crate having a bottom wall, side walls comprising fixed sections attached to the bottom wall and depending below the plane thereof, movable sections pivotally mounted upon the bottom wall to fold inwardly therefrom, said movable side-wall sections being provided with transversely-aligned guideways, and the fixed side-wall sections being provided with guideway extensions, end walls fitted to slide at their side edges in said guideways, and pivoting means, consisting of anti-friction-disks, and spindles carried by the side edges of the end walls, said disks engaging aligned guide-grooves in the walls of the guideways, substantially as specified. 100

7. A crate having a bottom wall, side walls mounted upon the bottom wall to fold inwardly, and provided with terminal transversely-aligned guideways, and end walls provided at their side edges, and contiguous to 110 their upper edges with opposite guides fitting in said guideways for movement toward and from the plane of the bottom wall, the end walls having a pivotal movement, with their fulcrums in the horizontal planes of said 115 guides, to adapt them to fold parallel with the bottom wall, substantially as specified.

In testimony that I claim the foregoing as my own I have hereto affixed my signature in the presence of two witnesses.

OREN ROSE.
